UNITED STATES PATENT OFFICE

JOHN N. HAZEN, OF HOLYOKE, MASSACHUSETTS, ASSIGNOR TO HAZEN PAPER COMPANY, OF HOLYOKE, MASSACHUSETTS, A CORPORATION OF MASSACHUSETTS

DESIGN FOR BOX COVERING PAPER OR SIMILAR MATERIAL

Application filed April 15, 1931. Serial No. 39,487. Term of patent 7 years.

To all whom it may concern:

Be it known that I, JOHN N. HAZEN, a citizen of the United States, residing at Holyoke, in the county of Hampden and State of Massachusetts, have invented a new, original, and ornamental Design for Box Covering Paper or Similar Material, of which the following is a specification, reference being had to the accompanying drawing, forming part thereof.

The figure of the drawing is a plan view of a piece of box covering paper showing my design.

The unit of the design is contained within

the area defined by the dot and dash lines A—B—C—D. The unit beginning at the angle —C— at the lower left edge is repeated at the angle —X— appearing substantially midway the vertical dot and dash lines at the right, while the unit beginning at the angle —D— at the lower right is repeated at the angle indicated —Y— appearing midway the left vertical dot and dash lines.

I claim:

The ornamental design for box covering paper or similar material substantially as shown and described.
